Primary Examiner — Thomas Johannes*Assistant Examiner* — Keith Frank(74) *Attorney, Agent, or Firm* — Andrew F. Young, Esq.; Lackenbach Siegel, LLP(57) **CLAIM**

The ornamental design for a packaging container, as shown and described.

DESCRIPTION

FIG. 1 is a front, right side perspective view of a packaging container showing my new design;

FIG. 2 is a front, left side perspective view thereof;

FIG. 3 is a front elevation view thereof; the rear view elevation view being a mirror image of the front elevation;

FIG. 4 is a left side elevation view thereof;

FIG. 5 is a right side elevation view thereof;

FIG. 6 is a top plan view thereof; and,

FIG. 7 is a bottom plan view thereof.
